COVERED BOWL

George Y. Matsumoto, Honolulu, Territory of Hawaii

Application June 11, 1954, Serial No. 30,934

Term of patent 14 years

(Cl. D44—15)

Fig. 1

To all whom it may concern:

Be it known that I, George Y. Matsumoto, a citizen of the United States and a resident of Honolulu, Territory of Hawaii, have invented a new, original, and ornamental Design for a Covered Bowl, of which the following is a specification, reference being had to the accompanying drawings, forming a part hereof.

I claim:

The ornamental design for a covered bowl, as shown.
